UNITED STATES PATENT OFFICE.

CHARLES W. LEFLER, OF BOISE, IDAHO.

EXTENSION SICKLE FOR MOWING MACHINES.

Application filed March 10, 1921. Serial No. 451,117.

To all whom it may concern:

Be it known that I, CHARLES W. LEFLER, resident of Boise, in the county of Ada and State of Idaho, citizen of the United States, have invented certain new and useful Improvements in Extension Sickles for Mowing Machines, of which the following is a specification.

This invention relates to extension sickles for mowing machines, and particularly to a device to be attached to parts of a mowing machine and to be used to cut at any angle from the vertical outwardly.

An object is to provide an attachment which may be applied to the shoe of the sickle of any type of mowing machine and which presents a rigid and well supported and braced structure thus insuring efficient operation in cutting at any angle.

A further object resides in providing for adjustment of the sickle and bar, and in arranging means to hold the adjustments.

A still further object is to provide an apparatus of simple and inexpensive construction which can be readily manufactured and which is applied without requiring the use of special tools or the services of a skilled mechanic; and, while in use will give an operating efficiency equivalent to a permanently constructed mechanism.

With these and other objects in view which will be apparent from the drawings, specification and claims, this invention includes certain novel features of construction and combinations of parts which will now be set forth.

In the drawings:

Figure 1 is a side elevation of one of the ground wheels of a mowing machine showing the device of my invention applied thereto.

Fig. 2 is a top plan view of the structure.

Fig. 3 is a front elevation.

Fig. 4 shows a detail of the drive connection.

Fig. 5 is an enlarged detail of the adjusting means to hold the angle of the cutter bar.

The ground wheel 1 of the mowing machine has a main frame member 2 of substantially U-shaped form extending upon opposite sides thereof and this frame member is mounted upon the axle 3 of the machine. The frame member is disposed with the loop thereof rearwardly and the forward ends are brought together and riveted or

otherwise secured. Supporting frame members 4 are connected with the main frame member on opposite sides of wheel 1 to extend forwardly and have their free ends secured together substantially vertically above the secured ends of the main frame member. Braces 5 and 6 are connected between the main and the supporting frame members and a rigid supporting frame structure is thus provided.

An open bevel gear 7 is mounted rigidly on the ground wheel 1 concentrically around axle 3 to turn with the wheel, and a bevel pinion 8 fixed on a shaft 9 mounted in bearings 9' on the main frame member is in mesh with the bevel gear 7. At the lower end of frame member 2 a hollow shoe 10 is provided, this shoe being shaped to slip over the shoe of the mowing machine and being secured thereon by a single bolt or other means which will allow for slight play between the main machine and the auxiliary structure. This shoe 10 has a cutter bar 11 given swinging mounting thereon, this cutter bar being of ordinary type with the possible exception that the fingers be made somewhat longer than usual so that the grass or grain being cut will be more readily picked up.

The knives are driven from the usual pitman 12, and the shaft 13 of this pitman is connected by a universal joint at 14 with shaft 9, a direct operating drive being thus made.

To give lateral support and bracing to the frame structure one or more pipe braces as indicated at 15 may be extended from the extension structure to the frame of the mowing machine, to which the braces will be attached by means of U-bolts or other suitable fastenings. The braces can be bent or shaped to suit the requirements and to give proper clearance.

At the upper end of bar 11 a rod 16 is pivotally connected, this rod being fitted slidably through a holder 17 mounted on the ends of supporting frame members 4, and a set screw 18 is provided to be tightened against rod 16 to hold adjustments thereof. By this means this sickle bar is held in any desired angular adjustments from the vertical to the horizontal position, and may even be dropped with its outer end angularly below the horizontal.

In the construction of the extension sickle structure guards of the necessary design will

be applied for the protection of the working parts, and the structure will be otherwise built with a view to meeting any special requirements in use.

5 While, in the foregoing, I have described specific embodiments, and have mentioned only certain possible modifications, and have illustrated only one manner of attachment, it will be appreciated that in practice I do not limit myself to such specific details as herein set forth, but may resort to any practical modifications falling within the scope of the invention as defined in the appended claims.

10 15 I claim:

1. An extension sickle for mowing machines including with a substantially U-shaped main frame member to be mounted on the axle of a mowing machine and embrace one of the ground wheels thereof, supporting frame members and braces associated with the main frame member to provide a supporting frame structure extending forwardly and substantially in vertical line with the shoe of the mowing machine, a hollow shoe mounted on the lower portion of the frame structure to receive and be secured upon the shoe of the mowing machine, an extension sickle structure pivoted at one end upon the supporting frame adjacent the hollow shoe to swing to any angle from the vertical outwardly, a rod pivoted on the outer end of the extension sickle bar, a holder mounted on the main

35 frame through which said rod is slideable and by which adjustments of the extension sickle are held, and means to operate the extension sickle.

2. An extension sickle for mowing machines including with a substantially U-shaped main frame member to be mounted on the axle of a mowing machine and embrace one of the ground wheels thereof, supporting frame members and braces associated with the main frame member to provide a supporting frame structure extending forwardly and substantially in vertical line with the shoe of the mowing machine, a hollow shoe mounted on the lower portion of the frame structure to receive and be secured upon the shoe of the mowing machine, an extension sickle structure pivoted at one end upon the supporting frame adjacent the hollow shoe to swing to any angle from the vertical outwardly, a rod pivoted on the outer end of the extension sickle bar, a holder mounted on the main frame through which said rod is slideable and by which adjustments of the extension sickle are held, a gear mounted on the ground wheel embraced by the supporting frame, a shaft having driving connection to the extension sickle, and a pinion on said shaft meshing with the gear on the ground wheel.

50 55 60 65 In testimony whereof I hereunto affix my signature.

CHARLES W. LEFLER.
